(57) **CLAIM**

The ornamental design for a syringe pump, as shown and described.

DESCRIPTION

FIG. 1 is a front, top, and right-side perspective view for a syringe pump, showing our new design;

FIG. 2 is an upwards sectional view taken from FIG. 1 thereof;

FIG. 3 is a downwards sectional view taken from FIG. 1 thereof;

FIG. 4 is a front elevation view thereof;

FIG. 5 is a back elevation view thereof;

FIG. 6 is a right side elevation view thereof;

FIG. 7 is a left-side elevation view thereof;

FIG. 8 is a top plan view thereof; and,

FIG. 9 is a bottom plan view thereof.

The broken lines depict portions of the syringe pump that form no part of the claimed design.

1 Claim, 9 Drawing Sheets
